FURNACE CONSTRUCTION

Horace E. Woolery, St. Paul, Minn.

Application May 31, 1938, Serial No. 210,903

3 Claims. (Cl. 126—110)

This invention relates generally to improvements in heating devices or furnaces, and more particularly to improvements in central heating units of the oil burning type and in which air from the heated enclosure is forcibly circulated through the heating unit and recirculated in the enclosure.

Units of this type, with which I am now familiar, generally employ a fan for circulating and recirculating the air and employ a separate fan for supplying the air needed for the oil burner. This assembly entails a needless duplication of parts, in that two separate fans, and operating motors therefor, are used, and in addition, since the air for the burner is generally taken from the room or space in which the unit is located, there results a depletion of pure air therein. In respect to the latter fault of the previous installations, it has been noted that the use of the air from the basement wherein the unit is ordinarily located has often necessitated an unreasonable amount of ventilation therein in order to supply adequate fresh air for the burner. Since the basement is ordinarily used but very little, this admission of outdoor air, in excess of the normal requirements for ventilation, represents added heating load and a loss in heating efficiency of the plant as a whole. My invention, therefore, has as its primary object the provision of a heating unit or plant in which the air required for the burner is taken entirely from within the heated enclosure instead of from some external source, such as the basement. Inasmuch as adequate ventilation of the heated enclosure must be provided in any event, for the sake of the health of the occupants thereof, this air taken from the enclosure for the burner represents no added load to the heater.

Another and equally important object of my invention is to provide a heating unit wherein the air for the burner is not only taken from the heated enclosure, but is also circulated and carried to the burner by the same fan which circulates the air through the heating unit as a whole. In this manner, then, a single fan and motor are caused to perform two distinct functions, that of circulating the air and feeding air to the burner, and one complete fan and motor assembly is eliminated from the cost and upkeep of the heating unit.

Another object is to provide a heating unit or assembly of this kind wherein the circulated air taken from the heated enclosure, after a small fraction thereof has been diverted to the burner, is blown through a heating or radiator element

to be heated thereby, and is then recirculated through the room. The said heating element is designed to provide a maximum of heating surface in a relatively small space, and is so designed that all of said surface is exposed to the heat and to the air currents circulated by the fan or blower to thus obtain the maximum possible efficiency in the heat transfer to the air.

Another object is to provide, in a heating plant of the kind described, a novel and extremely effective and simple assembly of air circulating fan, motor, and oil pump, all arranged in compact form and in such manner that a single motor operates both the fan and pump for supplying air and oil to the burner and for circulating the air from the heated enclosure through the plant.

A further object is to provide an assembly of this kind wherein the air for the burner is tapped or taken from the main air stream circulated by the fan, and is carried to the burner through a passageway or duct of relatively small cross sectional area so that the air enters the burner at relatively high velocity. This feature has been found to completely eliminate what is generally termed "flutter" of the burner flame, and which is actually a pulsating action of the flame due to lack of air and proper combustion. To further regulate the velocity of the air a Venturi tube may be arranged to feed the air from the circulating fan to the burner.

Still a further object is to provide a heating unit or assembly having the foregoing desirable features, but which is extremely compact in size and inexpensive in both initial cost and upkeep.

The foregoing and other objects, together with means whereby the same may be carried into effect will best be understood from the following detailed specification, reference being had thereto in the accompanying drawings, in which:

Fig. 1 is a vertical and longitudinal sectional view through a heating unit or plant constructed in accordance with my invention.

Fig. 2 is a fragmentary cross section, along the line 2—2 in Fig. 1, showing only the upper portion of the fire box and lower portion of the heating element.

Fig. 3 is a horizontal cross section along the line 3—3 in Fig. 1.

Fig. 4 is a fragmentary cross section through the upper portion of the unit, taken along the line 4—4 in Fig. 1.

Referring now with more particularity to the drawings, the essential elements of my invention

are shown as assembled within a suitable housing A to form what is known as a central, or unit, heater designed to be located in the basement or other out of the way room of the building and 5 having air inlet and outlet openings B and C which are connected by suitable ducts, piping or floor grills with the enclosure to be heated. These openings B and C are, accordingly, formed in the top of the housing A, and a central partition 10 D in the housing is located between these openings to divide the housing into two large separate chambers E and F, hereinafter known as the fan and heating chambers, respectively.

A fire box 5 is located in the lower portion of 15 the chamber F and comprises the metal pot 6 lined with fire brick 7 and having a cover plate 8. An oil burner 9 of any conventional type is located in the air and draft tube assembly 10 and which in turn is inserted into the fire box 5 20 through openings 11 in the partition D and the fire brick lining 7 so that the flame end of the burner enters the fire box while the inlet end projects into the lower portion of chamber E.

The heating or radiator element, designated 25 generally at 12, is made up primarily of a long sheet of metal which is reversely folded back upon itself a great number of times to provide a plurality of oppositely opening flat channels or flues separated by intervening folds in the 30 metal sheet. The radiator thus formed is set on end on the cover plate 8 of the fire box 5, and a back plate 13 is welded to the vertical back side of the assembly to close all of the channels thereat, except as will presently appear. The 35 cover plate 8 has an opening 14 coextensive with the bottom area of the radiator 12, and over which the radiator is mounted and secured by welding around its lower edge. The channels or flues formed by this folding of the sheet metal 40 for the radiator 12 are designated at 15 and 16 and are respectively termed the fire and air channels, as indicated by their respective uses. These channels are vertically extended, and the air channels 16 open at their upper ends and at the 45 side opposite the back plate 13, while the fire channels 15 are closed all around except over the opening 14 in the fire box cover plate 8. The intervening folds 17 defining these channels 15 and 16, or course, isolate each air channel from 50 the adjacent fire channels. The folds or walls 17 at their lower ends are spread or flared apart angularly at the lower end of each fire channel 15, and meet at their extremities where they are welded together at 18 to isolate and completely 55 close off the lower end of each air channel 16. Also secured between these walls 17 and in the lower ends of the air channels 16 are the heat radiating fins or bars 19 welded in place at the junction lines 18 and being coextensive therewith. The back plate 13 has openings 20 which 60 communicate with the angular lower end portions of the channels 16 and extend upwardly to about the level of the upper edges of the fins 19.

A smoke pipe 21 extends transversely across 65 the upper end of the radiator 12, and is welded thereto at 22. The upper ends of the fire channels 15 are closed at each side of this pipe 21, as designated at 23, but communicate with the pipe 70 through openings 24. On the other hand, the air channels 16 are open at each side of the pipe 21 but are closed adjacent the pipe by walls 25 and the arrangement, therefore, is such that fumes or smoke traveling upwardly through the 75 fire channels 15 may enter the smoke pipe while

air moving upwardly through the air channels 16 may flow past, but cannot enter, the pipe. One end of the pipe extends outwardly through the housing A for connection to the chimney (not shown), while the other end may be closed as at 5 26 in order to positively seal the chamber F from any gases or smoke which may arise from the burner 9.

A circulating fan or blower assembly, designated generally at 27, is provided in the chamber 10 E, and comprises a housing 28 which is secured at 29 to the partition D so that the outlet opening 30 of the housing communicates with the chamber F through an opening 31 cut in the partition just above the level of the fire box 5. The fan 15 rotor 32 is journaled in the housing 28 by an axle 33, and this fan preferably, though not necessarily, is of the type embodying a great number of transversely arcuated, angularly set blades or paddles 34 which are spaced around the end rims 20 35. Air from the chamber E enters the housing 28 through openings 36 in each end thereof, and flows into the fan rotor 32 which, when rotated rapidly in the direction indicated by the arrow, discharges the air at high velocity through the 25 opening 31 and into the chamber F. This air, in discharging as described, flows along the lower wall 37 of the housing, as designated by the arrows.

The fan rotor axle 33 is journaled in bearings 38, and at one end carries a pulley 39 over which is trained a drive belt 40. This belt also engages the pulley 41 of an electric motor 42 which is mounted atop the fan housing 28 to drive the fan. This motor also serves, in accordance with 35 one of the objects of my invention, to drive the fuel pump 43 to which it is connected and assembled as a unit, and this pump forces the oil or fuel to the burner 9 through the pipe 44.

In further carrying out my invention, and as 40 one of the most important objects thereof, I provide means at 45 by which a small part or quantity of the air moved by the fan 32 is tapped off from the main air stream and caused to enter the burner housing 10. This tap line or duct 45 45 comprises a tubular member of any suitable kind which extends from an opening 46 formed in the lower wall 37 of the fan housing 28 near the outlet of the fan and to another opening 47 formed in the burner housing or tube 10. As 50 here shown, and for the purposes of facilitating installation of the parts, the member 45 comprises tubular couplings or collars 48 which are secured by flanges 49 (or by welding) around the openings 46 and 47, and which are joined by a 55 coupling sleeve or tube 50 telescopically assembled. A butterfly valve 51, or equivalent means, may be located in the member 45 to control the amount of air flowing therethrough.

In operation, the burner 9 heats the interior 60 of the fire box 5, and this heat flows up through the fire channels 15 to heat the walls 17 of the radiator to a very high temperature. At the same time, the fan rotor 32 draws in air through the openings 36 and discharges this air into the 65 chamber F where it enters the open frontal sides of the air channels 16 and flows upwardly therein in contact with the heated walls 17. The air is thus heated and rises through the opening C to the heated enclosure, and, after being circulated 70 therein, it is drawn back through the opening B by action of the fan 32. There results, then, a continuous circulation and recirculation of the air, during the course of which it is heated by contact with the heated walls of the radiator as- 75

sembly 12. It will be readily evident that, due to the great number of, and great area of, these walls 17, the heat transfer will be rapid and efficient, and a high heating efficiency will be obtained. This is true even though the unit is relatively compact due to the novel manner of fabricating the radiator from a length of folded sheet metal so that, while it retains its effective area, it nevertheless occupies but a very nominal 10 space in the unit.

As the air enters the chamber F it will be noted that it flows, at least in part, directly along the bottom of the air channels 16 where it comes in contact with the parts where heated to their 15 greatest temperature, and a part of the air further flows through the openings 20 to thus travel upwardly along the back plate 13 and contact all surfaces of the radiator element. The lower flared ends of the fire channels 15 are, of course, 20 the hottest points in the entire radiator assembly, and it is important that the air contact these parts, as stated. This is accomplished by so locating the fan rotor 32 and air outlet 30 that their lower margins lie substantially in the same 25 horizontal plane as these parts. To prevent over-heating of the welded junctions 18 of the walls 17, the fins 19 are provided in order to present a greater heat radiating surface to the air. These fins may have apertures as denoted at 52, to 30 facilitate the air circulation.

A small part of the air stream flowing from the fan rotor 32 along the bottom wall 37 of the housing is diverted through the tubular tap member 45 to the burner tube 10, to supply the 35 air required for proper combustion. Inasmuch as this "burner" air represents but a small part of the air circulated by the fan, this tapping of the burner air from the main source entails no 40 added ventilating difficulties and permits a single fan and motor to carry out the functions heretofore assigned to two such assemblies. There results, therefore, a considerable simplification in assembly and reduction in cost. Furthermore, it has been found that, due evidently to the high 45 velocity of the air entering the burner through the tubular member 45 of relatively small diameter, the frequently encountered "fluttering" action of the flame of the oil burner is completely eliminated.

In this connection it will be noted that a Venturi tube or Venturi-shaped member 53 may be used in the tubular tap member feeding the burner to further regulate the velocity of the air entering the burner, and this represents an 50 important feature of the invention. In furtherance of the same action, the particular type of fan rotor as disclosed herein has the character-

istic of expelling the air radially at a very high velocity immediately adjacent the outer edges of its blades, and the air thus enters the tube 45 rapidly.

It is understood that suitable modifications may be made in the structure disclosed, provided that such modifications fall within the spirit and scope of the appended claims. Having thus fully disclosed my invention, what I claim as new and desire to secure by Letters Patent, is:

1. A heating furnace comprising a heating means, a radiator having vertically extended fire channels and air channels, the said fire channels communicating with the heating means, smoke outlet means at the upper ends of the fire channels, a back plate on the radiator and having openings at its lower portion communicating with the air channels, the opposite frontal side of the air channels being open, said channels having outlets at their upper ends, and means for circulating air through the open sides of the air channels and causing a part of said air to move along the lower ends of the channels and through the said openings.

2. A heating furnace comprising a heating unit, 25 a heat exchange structure supported over the heating unit and formed of sheet material to provide a series of vertically extended flat flues opening toward opposite vertical sides of the structure, a back plate extended across one vertical side of the structure and closing the sides of alternate flues, these flues being open at their lower ends over the heating unit to circulate heat upwardly therefrom and having smoke escape means at their upper ends, the intervening flues being closed at their lower ends and open 30 at their upper ends for escape of the heated air, and means for blowing air through the open sides of the said intervening flues and upwardly through the upper ends thereof at opposite sides 35 of the said smoke escape means.

3. A heating furnace comprising a heating unit, 40 a heat exchange structure supported over the heating unit and having a series of vertically extended flat flues opening toward opposite vertical sides of the structure, means closing the sides of alternate flues, these flues being open at their lower ends over the heating unit to circulate heat upwardly therefrom and having smoke escape means at their upper ends, the intervening flues being closed at their lower ends but open at one side and at their upper ends, a blower having air discharge means constructed and arranged to blow air inwardly over said lower closed ends of the flues and then upwardly 45 through their open upper ends.

HORACE E. WOOLERY.
